METHOD OF CONTROLLING THREAD TENSION

Melvin Mooney, Lake Hiawatha, N. J., assignor to
 United States Rubber Company, New York,
 N. Y., a corporation of New Jersey

Application July 18, 1946, Serial No. 684,602

9 Claims. (Cl. 242—45)

1

The present invention relates primarily to a novel method of controlling the tension of a rubber thread as it is wound upon the core of a golf ball, but the invention can be employed to control the tension of threads, cords, wires or filaments of various materials.

In manufacturing the better grade golf balls it is endeavored to wind the rubber thread on the golf ball core with the highest tension that can be used without producing breakage of the rubber thread during the winding operation, or within the ball after the core is wound. The maximum possible tension in the thread is desired because tests have shown that the higher the winding tension, the higher the resilience and the longer the flight of the ball when driven with a golf club. However golf ball thread cannot be made absolutely uniform in cross section by the methods now in use. The best that could be done with the conventional thread controlling apparatus available heretofore to tension the thread during the golf ball winding operation was to adjust the tensile force upon the thread to such a value that a small tolerable number of breaks occurred, while at the same time much of the thread was wound on the core at a tension less than the desired high tension. In other words the practice heretofore has been to wind the rubber thread on the core under a selected constant load, but the load must be chosen not to over-stretch those portions of the thread that happen to be undersized, with the result that those portions of the thread that happen to be oversized are understretched. In the finished ball the tension of the thread is therefore less in some regions than it should be.

The purpose of the present invention is to change the control of the tension of the thread being wound from one of tensile force to one of tensile stress. If the tensile force is continuously adjusted to maintain the tensile stress constant, a high mean stress can be utilized with a minimum of thread breakage, and a golf ball will be produced that is uniformly high as to thread tension.

While, as above stated, the present invention was developed primarily to maintain the tensile stress constant in highly elastic thread, such as the rubber thread of golf balls, the method of the present invention may be employed to maintain the tensile stress constant in threads or filaments having a much lower degree of stretch.

The present invention makes use of the well known physical law which states that the natural frequency of vibration of a thread stretched be-

2

tween two fixed points is determined by the ratio of the stretching force to the linear density (mass per unit length along the thread). This ratio can also be expressed as the ratio of the tensile force stretching the thread to the product of the volume density times the cross sectional area of the thread. In the rubber thread used in winding the body of golf balls the density is practically constant, but the cross sectional area exhibits uncontrolled variations. It follows from this physical law that if the tensile force is automatically and continuously adjusted so that the natural frequency of vibration of a definite length of the advancing thread is held constant, then the tensile force per unit cross-section area, that is, the stress, will necessarily be constant and can be maintained at a high value; and this is what is desired to produce a golf ball of high resilience.

It will appear from the foregoing that if a rubber thread being wound upon a golf ball core under tension is caused to pass over two spaced points such as small pulleys spaced a fixed distance apart, and the free length of thread between these two points is kept vibrating at its natural frequency, the rate of such vibration will vary (1) with the tension of the thread and (2) with the size of such thread.

As above pointed out it is not practical to produce a thread under the present methods of manufacture which will run absolutely uniform as to size, therefore, in accordance with the present invention it is proposed to regulate the tensile force such that the natural frequency of vibration remains substantially constant, by increasing the force when the thread runs over size and decreasing the force when the thread runs under size. The effect of this will be to wind the thread under uniform tensile stress instead of under uniform tensile force as has been the practice heretofore.

To summarize the foregoing, the present invention resides in the method of controlling the tensile stress in an advancing thread by advancing the stretched thread so that it passes two points spaced a fixed distance apart, vibrating this length of thread, measuring the natural frequency of vibration by suitable means, and varying the tension upon the thread in accordance with said measurement so as to maintain the natural frequency of vibration of this length of thread substantially constant.

One method for measuring the natural frequency of the thread is to impose upon the thread a vibration, or periodic impulse, of fixed frequency slightly different from the natural fre-

55

quency, and by means of a suitable detecting device connected to an intensity meter to measure the intensity, or the amplitude of the vibration. This method makes use of the resonance curve, which is the graph showing the amplitude of the continuous vibration as it varies with the frequency of the impressed vibration. Such a curve has a maximum at the natural frequency and drops sharply on both sides of the maximum. The rate at which the curve drops as the impressed frequency departs from the natural frequency depends upon the rate at which the vibrational energy of the thread is dissipated. Since the rate of dissipation is essentially constant for a given system, the resonance curve remains essentially constant in form as the thread advances; and hence the measured amplitude of continuous vibration may be used as a measure of the difference between the impressed frequency and the natural frequency. With the impressed frequency fixed and known, this constitutes a measurement of the natural frequency.

One form of apparatus applying this method in effecting automatic control of thread tension is shown in the accompanying drawing wherein;

Fig. 1 is a more or less diagrammatic view of the apparatus; and

Fig. 2 is a similar view of a modified part.

The thread control mechanism herein contemplated is shown in connection with a golf ball winding machine having the casing 10 adapted to support and rotate one of the golf ball winding heads 11, which head has the spaced frusto-conical disks 12 adapted to support the ball B upon which the rubber thread T, is being wound. The golf ball winding machine partially illustrated in the drawing may be of the general type disclosed in the Cobb Patent No. 1,270,009, or it may have any other preferred or well known construction.

The thread T being wound upon the ball B may be supplied from any suitable source such as the spool 13 which is rotatably supported at 14 upon a supporting beam 15, and as the thread unwinds from this spool 13 it passes downwardly about the floating pulley 16 and then upwardly over the pulley 17 supported by the beam 15. The pulley 16 is rotatably mounted at the outer end of a swinging arm 18 that is pivotally secured at 19 to a fixed support 20 and this arm 18 has suspended therefrom a number of weights 21. The rotation of the spool 13 as the thread T is unwound therefrom is retarded, in the construction shown, by the brake band 22 which is looped about a flange or pulley connected to this spool; one end of the brake band is anchored at 23, while the other end is secured to the rocking arm 18 at 24. The construction is such that a nearly uniform tension will be placed upon the rubber thread T as it passes upwardly around the pulley 17, since if a reduction in the tension in the thread occurs the arm 18 will swing downwardly to increase the brake action, and as the tension upon the thread increases the arm will be raised to reduce the brake action.

This tension mechanism is not new and is not an essential part of the present invention but is preferably provided to give a preliminary adjustment of the thread tension to approximately the desired value. The finer adjustment of the thread tension to the exact value desired is made in accordance with the present invention so as to maintain the tensile stress in the thread T as it is wound on the ball B substantially constant within narrow limits in spite of variations in thread size. This is accomplished in the con-

struction shown by providing the thread contacting drum 25 which is rotatably supported by the beam 26. The thread T may be looped around an idler roll 25' to increase the length of contact with the drum 25, thus to prevent it from slipping. The drum 25 has rigidly secured thereto the brake wheel 27 about which the brake band 28 is looped. One end of this brake band is anchored at 29 and the other end is secured to the iron armature or core 30 which moves up and down in the electromagnet coil 31 which is supported in a fixed position by the support 32.

The friction which the brake band 28 exerts upon the brake drum 27 is controlled, in accordance with the present invention, so as to maintain the frequency at which the portion of the thread T vibrates between two fixed points substantially constant. To this end in the construction shown the freely turning rollers 34 and 35 are provided, at a fixed distance apart, so that the tensioned thread will pass over these rollers as it approaches the ball B being wound. Various means may be provided to keep the length of thread B extending between these pulleys 34 and 35 vibrating.

In order to vibrate this length of thread at a fixed frequency near the desired natural frequency, the pulley 34 may be rotatably supported by an upright 36 that is mounted on a spring arm 37 such as a metal bar one end of which is rigidly secured at 38 to the supporting frame 39. The spring 37 carries the weight 37' which can be adjusted in its horizontal position so as to give the desired natural frequency of vibration of the spring. Means should be provided for causing the arm 37 to vibrate at its natural frequency, and the means shown to this end comprise the fixed solenoid coil which is disposed below the arm as shown. An armature 43, which is attached to

one face of the arm 37, projects into and terminates within the coil 41. Attached to the other side of the spring arm 37 is the short leaf spring 40, on which is mounted the microphone button 42. The microphone 42 and the coil 41 are connected in series through the circuit 44 to a source of constant D. C. voltage. The spring arm is thus maintained in vibration at a frequency determined by the adjustable weight 37' and at an amplitude determined by the adjustable voltage connected through the line 44. If, for example, the desired natural frequency of the thread is 1000 vibrations per second, the frequency of the spring arm would be adjusted to that slightly larger value, perhaps 1050, for example, which is at or near the point of greatest slope of the resonance curve for a rubber thread of natural frequency 1,000. This frequency of greatest slope in the resonance curve is likewise that fixed impressed frequency for which the amplitude of a rubber thread of adjustable natural frequency increases most rapidly as the natural frequency is increased above 1,000. Under these conditions the amplitude of vibration of the thread, as previously stated, will increase rapidly as its natural frequency approaches that of the constant imposed frequency, and will decrease rapidly as the difference between the imposed frequency and natural frequency increases. Therefore, under these conditions the amplitude of the thread vibration is a sensitive measure of the natural frequency of the thread at any instant, and of variations in the natural frequency.

The frequency of the thread vibration at any instant may be determined, according to one method, by using a microphone to detect the

sound of the vibrating thread and measuring the sound frequency with a suitable frequency meter.

In the construction shown the amplitude of the thread vibration is measured in the following manner. The pulley 35 is rotatably mounted on a post 45 which is secured to the flat spring 46 mounted on the supporting frame 39. The post 45 has attached thereto a dynamic microphone pick-up 47. In this arrangement the angle at which the vibrating rubber thread approaches pulley 35 varies periodically with the thread vibrations. As a result of this periodic variation in angle, there is also a periodic variation in the vertical component of the force exerted by the thread on the pulley 35. This periodic vertical force of the thread has an amplitude which is proportional to the amplitude of vibration of the thread; and it will therefore cause the pulley 35 and post 45 to vibrate with an amplitude which is proportional to the amplitude of vibration of the thread. The signal from the pick-up therefore will be proportional to the amplitude of vibration of the thread. In the construction shown the signal from the pick-up 47 passes by means of the wires 48 to the amplifier 49, and after having been amplified, passes to the rectifier 50, and thence by the wires 51 to the solenoid coil 31 above mentioned.

In order to operate the system described, the combined braking force due to the two weights 21 and 33, is adjusted so that the tensile force exerted upon the thread with no current in the coil 31 will be slightly greater than the tensile force which will be required for the thickest part of the rubber thread T being wound. Then, when the thread is first started winding on the ball B, the tension, starting at a low value, will build up as the rubber thread between the supply spool 13 and ball B is stretched without any movement of the spool 13. During this time the natural frequency of the thread will lie at some point below the frequency at which the pulley 34 is being vibrated by the coil 41, and the amplitude of the thread vibration at this time will have a low value. When however the thread tension increases to such extent that the natural frequency approaches more closely the impressed frequency, the amplitude of thread vibration, and so of the microphone signal at 47, will both increase rapidly. The amplifier 49 should be adjusted so that the lifting force of the core 30 will be just sufficient to let the pulley 25 turn at a constant speed when the natural frequency of the thread has attained its predetermined desired value. The amplitude of thread vibration will at this time be most sensitive to small changes in its natural frequency, as previously explained. With this adjustment, if the thread stress becomes too great, due to a local decrease in the thread section, so that the natural frequency approaches more closely that of the imposed frequency the amplitude of thread vibration will increase, and this will cause an increase in the lifting force of the core 30. The upward movement of this core will decrease the braking action on the drum 27 and permit a temporary increase in the velocity of rotation of the pulley 25 to thereby reduce the tension on the rubber thread. Similarly, a slight local increase in thread-section will result in an increase in braking action at 27 to temporarily retard rotation of the drum 25 to increase the thread tension. If this automatic action keeps the amplitude of thread vibration within narrow limits, the natural frequency will be maintained nearly constant, which is what is desired to keep

the tensile stress of the thread being wound upon the ball approximately constant.

While the means just described for automatically controlling the tension of the thread T, or other automatic means to this end, is considered highly desirable, such automatic feature is not essential in all embodiments of the invention. For example, the brake controlling core 30 and coil 31 could be omitted and an ammeter 52 could be connected to the rectifier 50 to thereby indicate visually to the machine operator variations in the electric energy from the pick-up 47. With this visual reading the operator could manually adjust the brake band 28 to vary the tension of the thread T.

It will be seen from the foregoing that as the running thread T passes over the spaced pulleys 34 and 35 the natural frequency of vibration of this portion of the thread will be continuously measured either directly or indirectly, and the tensile force opposing the winding action will be continuously adjusted to keep the natural frequency constant within narrow limits, to thereby control the tensile stress of the winding thread independently of variations in its size and elastic modulus. In practicing the present method it is important that the velocity at which the thread T advances be kept sufficiently small that the distance traversed during one cycle of vibration will be small compared with the distance between the pulleys 34 and 35. This is equivalent to saying that the velocity of advance must be kept small compared with the velocity of propagation of a wave form along the stretched thread.

Having thus described my invention, what I claim and desire to protect by Letters Patent is:

1. The method of controlling the tensile stress in an advancing thread, which consists in advancing the thread under tension past two points spaced a fixed distance apart, vibrating the free portion of the thread between these points to set up periodic variations in the force exerted by the thread on one of said points, detecting variations in the said periodic force of the thread at such point due to changes in the amplitude of the thread vibrations, and adjusting the tensile force on the thread in accordance with the detected variations to thereby hold the natural frequency of vibration substantially constant, thereby to keep the tensile stress substantially constant in spite of variation in the size and elastic modulus of the advancing thread.

2. The method of controlling the tensile stress in an advancing thread, which consists in advancing the thread under tension past two points spaced a fixed distance apart, impressing a vibration of fixed frequency on the free portion of the thread between these points, measuring variations in the natural frequency of vibration of this portion of the thread by measuring variations in the amplitude of the impressed vibration, and varying the tension upon the thread in accordance therewith so as to keep the natural frequency of this portion of the thread practically constant, thereby to keep the tensile stress in the thread substantially constant and independent of variations in the size of the advancing thread.

3. The method of controlling the tensile stress in an advancing thread, which consists in advancing the thread under tension past two points spaced a fixed distance apart, vibrating the thread between these points to set up periodic variations in the force exerted by the thread on one of said points, continuously detecting variations in the said periodic force of the thread at

said point caused by changes in the amplitude of the thread vibration, and continuously adjusting the tension on the thread in accordance with such detected variations to hold the natural frequency substantially constant at a selected value, to thereby keep the pounds per square inch tension of the thread constant at a predetermined value.

4. The method of controlling the tensile stress in an advancing thread, which consists in advancing the thread under tension past two points spaced a fixed distance apart so that it may vibrate, subjecting this portion of the thread to a vibration of fixed frequency slightly different from the desired natural frequency and measuring variations in the natural frequency of the thread as evidenced by changes in the amplitude of thread vibrations, and adjusting the tension upon the thread in accordance therewith so as to keep the natural frequency of this portion of the thread practically constant at a predetermined value, thereby to keep the tensile stress substantially constant at a predetermined value in spite of variation in the size and elastic modulus of the advancing thread.

5. The method of controlling the tensile stress in an advancing thread, which consists in advancing the thread under tension past two points spaced a fixed distance apart, vibrating the free portion of the thread between these points at its approximately natural frequency, detecting the intensity of the periodic force which such vibrating thread exerts at one of said points, and adjusting the tensile force on the thread in accordance with this intensity to hold the frequency of thread vibration substantially constant, thereby to keep the tensile stress in the thread substantially constant and independent of variations in the size of the advancing thread.

6. The method of controlling the tensile stress in an advancing thread, which consists in advancing the thread under tension past two points spaced a fixed distance part, vibrating the free portion of the thread between these points at its approximately natural frequency, detecting changes in the periodic force which such vibrating thread exerts at one of said points, and automatically adjusting the tensile force on the thread as such changes are detected to hold the frequency substantially constant, thereby keeping the

tensile stress in the thread substantially constant.

7. The method of controlling the tensile stress in an advancing thread, which consists in advancing the thread under tension past two points spaced a fixed distance apart, impressing on the free portion of the thread a vibration of a frequency slightly different from the natural frequency corresponding to the desired tensile stress,

10 measuring the amplitude of the vibration, using it as a measure of the natural frequency of vibration and adjusting the tensile force in accordance therewith to keep the natural frequency substantially constant, thereby keeping the tensile stress substantially constant.

8. The method of controlling the tensile stress in an advancing thread, which consists in advancing the thread under tension past two points spaced a fixed distance apart, vibrating the thread between these points so that the force periodically exerted by it upon one of the points will vary with changes in its amplitude of vibration, electrically detecting variations in the periodic force of the thread at said point, and automatically adjusting the tension of the thread in accordance with such detected variations, thereby keeping the tensile stress of the thread at a selected value.

9. The method of controlling the tensile stress in an advancing thread, which consists in advancing the thread under tension past two points spaced a fixed distance apart, vibrating the thread between these points so that the force periodically exerted by it upon one of the points will vary with changes in its amplitude of vibration, electrically detecting by a microphone pick-up the variations in the periodic force of the thread at said point, and automatically adjusting the tension of the thread in accordance with such detected variations, thereby keeping the tensile stress of the thread at a selected value.
